Specification of Letters Patent.

Patented Apr. 6, 1915.

Application filed August 10, 1914. Serial No. 856,034.

To all whom it may concern:

Be it known that I, AXEL W. PETERSON, a citizen of the United States, residing at San Francisco, in the county of San Francisco and State of California, have invented new and useful Improvements in Vises, of which the following is a specification.

This invention relates to improvements in quick-acting vises for holding metallic objects, the object of the invention being to provide a construction which will be simple and inexpensive and which can be applied to all kinds and sizes of such vises.

In the accompanying drawing, Figure 1 is a longitudinal sectional view of one form of my improved device; Fig. 2 is an end view of the same; Fig. 3 is a cross section on the line 3—3 of Fig. 1; Fig. 4 is a broken bottom plan view of a stem.

Referring to the drawing, 1 indicates a stationary jaw formed with a base 2 and a screw 3 for securing it to a bench or other support. The body of said jaw is formed with a guideway 4 to guide the body 6 of the movable jaw 7 which is slidable on said base 2. The body 6 of the movable jaw 7 is, in cross section, of an inverted-U shape, this being a common form with this class of vises. Through the closed outer end of said body is a circular hole, through which passes a tube 9 having a thickened head 10, through diametrically opposite holes in which passes a slidable handle 11 for turning the tube. Said tube has secured on the inner portion thereof within said closed end a collar 12. Thus said tube is permitted to have no longitudinal, but only a rotary, movement. In said tube is screwed the threaded end of a stem 13 extending within the hollow body of the stationary jaw. The tube 9 has a reduced portion 5, one half of which is cut away and surrounding the stem 13 is a semi-cylindrical clamp 15, also threaded internally, around which and the reduced portion 5 is a split spring ring 20, which serves to press the clamp on to the threads of the stem, thus preventing the tube 9 slipping on the stem, unless the stem encounters resistance to turning. The threads of the stem extend only a short distance along said stem and the remainder of the stem has a longitudinal flattened portion 14 on one side of which is a square shoulder 16. The surface of the stem next the other side is formed with a longitudinal series of transverse cor-

rugations 17, the shape of the corrugated portions of the stem being slightly eccentric to the axis of the stem.

The outer portion of the base of the stationary jaw is formed with a longitudinal groove 18 having undercut sides, and in said groove is supported the beveled or flaring base of a retainer 19 having through the upper portion a cylindrical longitudinal hole through which the stem 13 can pass. After sliding the base of the retainer in the groove 18 a pin or screw 21 is driven into a hole in the base and serves to keep the retainer in position in the groove.

In the retainer is formed a longitudinal groove 22 opening in the bottom of said cylindrical hole. The bottom of said groove slopes upwardly toward the inner end of the stationary jaw, and in said groove a wedge 23 is retained by a flat spring 24, of which the upper end enters a slot or recess in a tail 26 extending from the rear end of said wedge and the lower end is bent and is inserted in a slot in the rear end of the retainer. The upper surface of the wedge is preferably concave to approximately conform to the cylindrical surface of the hole in the retainer, and is formed with transverse corrugations 27. One side of said wedge is higher than the other to form a shoulder 28. In its normal, or unclamping, position the stem is in such an angular position that the wedge is immediately under the flat portion of the stem. In this position, the stem can be freely slid longitudinally, and thus the movable jaw can be moved toward the stationary jaw to any desired position to clamp an object therebetween. Then, by giving the handle a small fraction of a turn to the right, or in the direction in which the handle is usually turned to clamp an object in the vise, the stem is turned by its frictional engagement with the tube 9, until the corrugations 17 thereof engage the corrugations 27 in the top of the wedge. It is for the purpose of insuring that there is sufficient friction between the tube and the stem to insure the turning of the latter with the former that I provide the split spring ring 20. When the corrugations 17 engage the corrugations 27, the stem can no longer slide freely longitudinally, but longitudinal movement can only be imparted thereto by further turning of the handle in the same rotary direc-

tion. As soon as resistance is offered to the inward movement of the movable jaw, the result of the further turning of the handle is to tend to move the stem outward, or away 5 from the stationary jaw, and thus also by reason of the engagement of the corrugations 17 and 27 to cause the wedge likewise to move in the same direction, or toward the movable jaw. Since the thinner edge of the 10 wedge is directed toward the movable jaw the result of this movement is to wedge the stem tightly in the retainer. Thus the stem is then held stationary, and a further turning of the handle causes the tube, and the 15 movable jaw moved therewith, to move toward the stationary jaw and to clamp the object. To unclamp the object, the handle is given a partial turn in a left-handed direction, and then, the friction between the 20 stem 13 and the tube 9 being greater than that between the corrugations of the stem and wedge respectively, the corrugations of the stem are moved out of engagement with the corrugations of the wedge, so that the 25 stem is turned about its axis until the shoulder 16 of the stem engages the shoulder 28 of the wedge, and the wedge lies immediately beneath the groove, and then the stem and movable jaw are free to move longitudinally. 30

Various slight changes are necessary to be made to adapt the vise for different uses.

I claim:—

1. In a vise, a stationary jaw having a 35 channel-way, a movable jaw having an inverted-U-shaped body and slidable in said channel-way, a retainer secured in the bottom of the channel-way within said U-shaped body and having a groove of which 40 the bottom slopes upward toward the movable jaw and having also a longitudinal

aperture with the bottom of which said groove communicates, a wedge in said groove, a stem passing through said aperture having a longitudinal flattened portion 45 and a shoulder on one side of said flattened portion and having on the other side of said flattened portion corrugations, the top of the wedge having corrugations, the stem having a threaded portion and a threaded 50 tube screwed on said threaded portion and movable with the movable jaw.

2. In a vise, a stationary jaw having a channel-way, a movable jaw having an inverted-U-shaped body and slidable in said 55 channel-way, a retainer secured in the bottom of the channel-way within said U-shaped body and having a groove of which the bottom slopes upward toward the movable jaw and having also a longitudinal 60 aperture with the bottom of which said groove communicates, a wedge in said groove, a stem passing through said aperture having a longitudinal flattened portion and a shoulder on one side of said flattened 65 portion and having on the other side of said flattened portion corrugations, the top of the wedge having corrugations, the stem having a threaded portion, a threaded tube screwed on said threaded portion and movable 70 with the movable jaw, and means for producing frictional engagement between the tube and stem, whereby the stem turns with the tube when free to so turn.

In testimony whereof I have hereunto set 75 my hand in the presence of two subscribing witnesses.

AXEL W. PETERSON.
